UNITED STATES PATENT OFFICE.

GEORGE S. MAXWELL, OF MADISON, NEW JERSEY, ASSIGNOR OF ONE-HALF TO HENRY DURELL CRIPPEN, OF NEW YORK, N. Y.

DESIGN FOR A SUPPORT FOR PUNCHING-BAGS.

SPECIFICATION forming part of Design No. 34,623, dated June 4, 1901.

Application filed May 8, 1901. Serial No. 59,345. Term of patent 14 years.

To all whom it may concern:

Be it known that I, GEORGES MAXWELL, a citizen of the United States, residing at Madison, in the county of Morris and State of New Jersey, have invented and produced a new and original Design for a Support for Punching-Bags, of which the following is a specification, reference being had to the accompanying drawings, forming a part thereof.

Figure 1 is a perspective of a support or bracket, showing my new design. Fig. 2 is a plan looking from the under side of Fig. 1.

As shown in the drawings, the leading or material feature of my design consists of a plate A, having an arm B projecting outwardly therefrom, and at the end of said arm a dome-shaped part C, having an aperture in the upper part thereof, as indicated at D, and

having the edge of its rim flanged or turned back to present an annular surface E.

It will be understood that the support may be attached in position, so that the dome opens upwardly or downwardly, the design being the same in either case.

Having described my invention, what I claim as new, and desire to secure by Letters Patent, is—

The design for a support for punching-bags, as herein shown and described.

In testimony whereof I have signed my name to this specification in the presence of two subscribing witnesses.

GEORGE S. MAXWELL.
